DOOR FRAME MOUNTING AND METHOD
OF PROCEDURE

Alois W. Pattiani, Oakland, Calif.

Application April 11, 1955, Serial No. 500,555

4 Claims. (Cl. 20—11)

My present invention relates to building construction and more particularly to an improved method for setting mill finished door frames in a wall or interior partition of a building under construction.

The principal object of my invention is to provide a method by which a mill finished door frame may be conveniently and accurately set in a rough timbered doorway in a building wall or partition.

Another object of the invention is to provide a method by which a door frame may be accurately positioned and secured within a rough timbered doorway opening on a particular center line irrespective of the actual location of the sides or jambs of the doorway opening and whether or not the timbers outlining the sides of the doorway opening are plumb.

Another object of the invention is to provide an improved method for setting mill finished door frames in the doorway opening of a wall which will insure a true and absolute centering and squaring of the door frame so that a door when hung therein will be free from binding at all points within the frame.

A further object of the invention is to provide a method by which improperly set or skewed cripples that define the sides of a doorway opening may be modified to provide a series of vertical aligned contact points for centering a door frame in the doorway opening with its side jambs in perfect parallelism and vertical with respect to a plumb line established therebetween said jambs extending at right angles through the doorway opening.

Other objects and advantages will be evidenced to those skilled in the art and in part pointed out hereinafter in connection with the accompanying drawing wherein there is shown by way of illustration and not of limitation a preferred embodiment of the invention.

In the drawing:

Figure 1 is a perspective view showing a preferred embodiment of the invention with the finished door frame in position.

Figure 2 is a fragmentary perspective view showing details of the arrangement with the finished door frame removed, and

Figure 3 is an enlarged perspective view showing a further detail of the arrangement illustrated in Figure 1.

To illustrate an application of this invention I have, in Figures 1 and 2 of the drawing, shown a portion of a partially finished interior wall of a building with plaster applied and designated by the numeral 10, the plaster being broken away to reveal details of my proposed construction and method of procedure. As here shown, the wall 10 is provided with a doorway opening that is defined by spaced vertical disposed roughly framed studdings 11 that are carried by bottom or sole plates 12 which are fixed to a rough planking 13 upon which the finished flooring of the room is generally applied.

For reinforcing such a wall at the doorway opening, there are also provided additional shorter lengths of studding 14 that are firmly secured in the doorway to

2

the studdings 11. These shorter lengths of studding 14, generally referred to as cripples, correspond in length to the height of the roughly framed doorway and serve as a support for a rough timber header 15 over the doorway opening. As these cripples 14 are secured firmly to the studding 11 at each side of the doorway opening, it will be seen that their spacing and vertical alignment will necessarily correspond with the spacing and alignment of the studdings 11 which, in being set up, may not be truly vertical or parallel with confronting faces extending at right angles through the doorway opening.

Mill finished door frames are generally furnished by the mill in a knocked down manner or completely assembled with the door, and the particular portions with which we are here concerned consist of two side jambs 16 and a head jamb 17. The head jamb 17 is shown in the drawing as dadoed into and fastened between the upper ends of the jambs 16 where it is secured, and when the finished door frame is finally nailed in the doorway opening, it thus determines the dimensions of the finished doorway.

In the past, under these conditions, and in order to set a finished door frame of this type between the cripples 14 with its side jambs 16 plumb and in properly spaced relation, the builder has resorted to the insertion of shims or blocks such as two or more oppositely arranged shingles or wedges, to fill in any excess space or clearance between the cripples 14 and the outer sides of the finished door frame before final nailing of the latter in place.

By my invention I avoid this cumbersome and hazardous or hit and miss method of procedure by cutting horizontally extending dados or grooves 18 at vertically spaced points along the confronting faces of the cripples 14 and mounting filler blocks 19 in these dados or grooves 18 in such a manner that they provide a series of accurately spaced and vertical and aligned faces or bearing points extending at right angles through the doorway opening with which, as shown in the drawing, the outer sides of a finished door frame 16 will engage when in final vertical position.

If the cripples 14 as finally set up, are found to be truly vertical or plumb and uniformly spaced throughout their length it is a simple matter to use blocks of a uniform thickness, without cutting the dados or grooves 18, along each of the cripples 14; but it more often happens that the cripples 14 are far from plumb and true when finally secured to the studdings 11 and the positioning thereof generally varies laterally and from top to bottom. It will be seen that even where the spacing of the cripples is uniform throughout their length, if they are not at right angles through the doorway opening or lean in the same direction, a non-uniform depth of the dados or grooves 18 in the confronting faces of the cripples 14 will be necessary if the finished jambs 16 of the door frame are to be plumb and properly spaced when finally set in the wall for the hanging of a door therein.

To provide for the above contingencies and to insure a perfect plumb and proper setting of the finished door frame with its side jambs 16 and its header 17 in the doorway opening between the opposed cripples 14, I establish a plumb line preferably centrally of the doorway opening, and from this plumb line the distance or depth A of each of the dados or grooves 18 in the respective confronting faces of the cripples is determined, and extended at right angles through said doorway, so that with filler blocks 19 of uniform thickness, seated in the grooves, there will be established a series of plumb and laterally aligned bearing surfaces against which the

outer vertical jambs 16 of the finished door frame may be firmly and finally secured as by nailing.

In other words, regardless of the deformities in the cripples and their rough positioning, by my method the bottoms of the dados, or grooves will all be aligned on a vertical plane extending at right angles to the doorway, and that therefore the filler blocks seated against these aligned bottoms and extending out of the grooves to receive the finished door frame (16 in Fig. 1) must be all of an equal thickness "C," at least as to each cripple, and may be as to both cripples. This does away with the heretofore general use of tapered shingles or shims, and constant level reading, and the projecting blocks provides a perfectly fitting perfectly squared set of bearing surfaces to receive and align a mill finished door frame with or without a door also mounted in the frame to its final position.

In Figure 3 of the drawing, I have shown the dados 18 as a greater vertical width than the filler blocks 19, but this can be a tight fit if desired or the blocks may be glued or held in place by a light finishing nail 21, and while I have shown only three such dados in each of the cripples 14 it is to be understood that a greater or lesser number may be employed if desired.

To facilitate a cutting of the dados or grooves 18 in the cripples 14 I have found that this can be accomplished in a simple and convenient manner by substituting a vertically disposed tool supporting column for the plumb line 20 and mounting a vertically and laterally adjustable dado saw or other groove forming or wood cutting tool thereupon. This particular device is to be the subject of a contemplated copending application in which it will be more fully described and claimed.

If for some reason it should be inconvenient to locate the plumb line 20 at the exact center of the doorway opening between the cripples 14, the matter of determining the depth of the dados 18 at either side thereof will only require a change, more or less, in the dimension "B" comparable to the off-center displacement of the plumb line 20.

While I have, for the sake of clearness and in order to disclose the invention so that the same can be readily understood, described and illustrated a specific form and arrangement, as applied to the setting of a door frame in a doorway opening, I desire to have it understood that the invention is not limited to the specific form disclosed, but may be employed in the mounting of window frames and the like and for other purposes that will suggest themselves to persons skilled in the art. It is believed that this invention is new and therefore all such changes as come within the scope of the appended claims are to be considered as part of this invention.

Having thus described my invention, what I claim and desire to secure by Letters Patent is:

1. The method of setting a finished door frame in a building wall having a roughly framed timbered doorway opening larger than the finished door frame, which comprises establishing a plumb line between the confronting faces of the doorway framing, forming a plu-

rality of grooves in said framing and spaced along said confronting faces, and extending at right angles through said doorway, all to the same depth as measured from said plumb line respectively as to said faces, positioning filler blocks of uniform thickness in said grooves to project therefrom for locating the finished door frame thereagainst to its final vertical position, and placing and securing the finished door frame in place against said blocks.

2. The method of setting a finished door frame in a building wall having a roughly framed timbered doorway opening larger than the finished door frame, which comprises establishing a plumb line between the confronting faces of the doorway framing, forming a plurality of grooves in said framing and spaced along said confronting faces, and extending at right angles through said doorway, all to the same depth as measured from said plumb line respectively as to said faces, positioning strips of uniform thickness in said grooves to project therefrom, locating the finished door frame against said strips to its final vertical position and securing the finished door frame in place by nails passing through said finished door frame and said strips into the confronting faces of said framing.

3. The combination comprising, a roughly framed timbered doorway opening and a finished door frame, grooves formed in and spaced along the confronting faces of the upright framing of the doorway opening of various depths into the framing as required to bring the bottoms of the grooves of each face into alignment on a vertical plane extending at right angles to the doorway, spacing blocks seated and secured in said grooves, all of the blocks of each face respectively being of uniform thickness greater than the depth of the grooves so as to project therefrom, and a finished door frame vertically aligned within and by contact with the projecting portions of the blocks and finally secured in such position.

4. The combination comprising, a roughly framed timbered doorway opening and a finished door frame, seats formed in and spaced along the confronting faces of the upright framing of the doorway opening of various depths into the framing as required to bring the bottoms of the seats of each face into alignment on a vertical plane extending at right angles to the doorway, spacing blocks seated and secured in said seats, all of the blocks of each face respectively being of uniform thickness greater than the depth of the seats so as to project therefrom, and a finished door frame vertically aligned within and by contact with the projecting portions of the blocks and finally secured in such position.
